(57) **CLAIM**

I claim the ornamental design for a bag, as shown and described.

DESCRIPTION

FIG. 1 is a perspective view of a bag;

FIG. 2 is a perspective, partially exploded view thereof;

FIG. 3 is a front side elevation view thereof;

FIG. 4 is a rear side elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown in the drawings appearing as short dash-short dash are included for purposes of illustrating environment and form no part of the claimed design. The broken lines appearing as long dash-dot indicate lead lines and form no part of the claimed design. The broken lines appearing as long dash-long dash indicate stitching and are part of the claimed design.

1 Claim, 8 Drawing Sheets
